UNITED STATES PATENT OFFICE

163,847

DRINK ACCESSORY CABINET

Karl Brocken, Milwaukee, Wis.

Application July 13, 1950, Serial No. 11,140

Term of patent 3½ years

(Cl. D52—2)

To all whom it may concern:

Be it known, that I, Karl Brocken, a citizen of the United States, residing at Milwaukee, in the county of Milwaukee and State of Wisconsin, have invented a new, original, and ornamental Design for a Drink Accessory Cabinet, of which the following is a specification, reference being had to the accompanying drawings, forming part thereof.

Fig. 1 is a front and end perspective view of the drink accessory cabinet, showing my new design; and

Fig. 2 is a plan view thereof, with the electrical cord shown in broken lines for illustrative purposes only.

I claim:

The ornamental design for a drink accessory cabinet, substantially as shown and described.

KARL BROCKEN.
